(57)

CLAIM

The ornamental design for a throttle, as shown.

DESCRIPTION

FIG. 1 is a rear perspective view of a throttle in accordance with our new design;

FIG. 2 is a front elevation view thereof;

FIG. 3 is a rear elevation view thereof;

FIG. 4 is a side view thereof;

FIG. 5 is a side view thereof, for the side opposite that of FIG. 4;

FIG. 6 is a top view thereof; and,

FIG. 7 is a bottom view thereof.

The broken lines shown in the drawings are only provided to illustrate the environment of the design, and form no part of the claimed design.

1 Claim, 4 Drawing Sheets
